CLOSABLE CABINET FOR THE COLLECTION AND SAFE STORAGE OF SOILED LINEN

Donald Ritchie Hughes, 20 Ave. La Croix, Sea Point, Cape Town, Cape Province, Republic of South Africa, and Mervyn Lorraine Olivier, Cape Town, Cape Province, Republic of South Africa; said Olivier assignor to said Hughes

Filed Feb. 5, 1962, Ser. No. 171,162

Claims priority, application Republic of South Africa, Feb. 19, 1960, 4,293/60; Oct. 17, 1961, R 1,991/61
18 Claims. (Cl. 232—43.2)

This invention relates to a closable cabinet for the collection and safe storage of soiled linen, more particularly for use in hospitals and other large institutions where a large amount of soiled linen has to be dealt with each day.

Objects of the invention are to provide a cabinet for this purpose which permits soiled linen to be easily deposited through a closable opening in its top end into a separate removable lockable container within the cabinet and thus prevent theft and exposure of the soiled linen to flies and air currents which might spread infection.

According to the invention, a cabinet for the collection and storage of soiled linen includes; a frame enclosed by an outer casing; an inner removable closable and lockable container within the outer casing; a closable filling opening in the top end of the cabinet through which to deposit soiled linen into the inner container; means to close and lock the inner container within the cabinet before it can be removed from the cabinet; and foot-operated shaking down means adapted to compact the soiled linen in the inner container. The said shaking down means may be interconnected with closure means co-acting with the filling opening, whereby said shaking down means is constrained to come into operation every time a quantity of soiled linen is deposited in the cabinet.

The inner removable and closable container is arranged to be locked in its closed condition to prevent theft of articles therefrom and to isolate the contents, and is preferably of bag-like form made from flexible sheet material. The locking of this inner container is arranged to take place before it can be removed from the cabinet by way of a lockable door opening in a side wall of the cabinet.

The closure means coacting with the top filling opening is so arranged that, although soiled linen can be readily deposited in the cabinet and into the inner container it cannot thereafter be withdrawn through the filling opening, which arrangement prevents theft of articles once they have been deposited in the cabinet. The filling opening may optionally include disinfectant means to provide a decontamination function.

To achieve this object, the closure means is in the form of a horizontally disposed inner drum member mounted within an outer similarly shaped casing for rotary movement with respect to such outer casing about its horizontal axis. The inner drum member is rotatably mounted by means of stub axles at its ends which are journaled in bearings provided in or outside of the end walls of the outer casing. In one arrangement, one of these stub axles projects through its bearing and an actuating lever arm fixed to such outer end, is linked by a connecting rod to the aforementioned foot-operated shaking-down means located at the bottom end of the cabinet.

Alternatively, one of the stub axles projects through its bearing and a toothed sprocket wheel keyed to such outer end is connected by a chain to a chain wheel or the equivalent operated by a foot-pedal located at the bottom end of the cabinet. Other and further alternative methods may be utilized as will be apparent to those skilled in the art. For example, a pedal-operated rack coacting with a pinion on a stub axle of the drum member may be used.

2

The inner drum member may rotate about its axis to bring its opening into a first position of alignment with the top opening of the outer casing to enable a batch of soiled linen articles to be deposited therein.

Subsequently the drum is rotated an angular distance sufficient to bring its opening into a second position of alignment with the bottom opening of the outer casing, whereupon the contents are free to fall out into the inner bag-like container. In this position, the top opening of the outer casing is of course closed so that the cabinet is sealed. Preferably rubber buffers are associated with the ends of the transverse pivot shaft to eliminate undue noise and shock during the shake-down operation.

The cabinet of the present invention, is an improvement over existing cabinets or containers for soiled linen used in hospitals, in that it enables soiled linen to be deposited easily and immediately at the point where it is taken out of use with complete security and safety (providing a proper system of control of the separate keys to the cabinet and to the inner bag-like containers is instituted) and without exposing the linen to flies and air currents, which may spread infection.

The shaking-down device, enables the maximum quantity of linen to be stored in the minimum space. Furthermore, the bag-like containers, while being light and readily portable for the conveyance of both soiled and clean linen between hospitals and laundries, are also easily cleaned and disinfected.

A further advantage is that the design of the cabinet and the inner container lends itself to the use of bacterial filters and decontaminating sprays which contribute towards the reduction of cross-infection from contaminated linen which is a serious problem in hospitals throughout the world.

To enable the invention to be more clearly understood and carried into practice, reference is now made to the accompanying drawings in which like references denote like parts throughout the several views.

In the drawings:

FIGURE 1 is a front view of a cabinet constructed according to the invention;

FIGURE 2 is a side view of the cabinet of FIGURE 1;

FIGURE 3 is an enlarged end sectional view of the top filling drum of the cabinet, shown in the open position to receive a batch of soiled linen;

FIGURE 4 is a similar view showing the filling drum in its discharging position;

FIGURE 5 is a side pictorial view of the cabinet with the sheet material forming the panels of the casing and the bag removed, for the sake of clarity;

FIGURE 5a is a part-sectional detail view showing how decontamination of the inner drum member is effected;

FIGURE 6 is a cut-away pictorial view of the lower part of the cabinet of FIGURE 5 as viewed from the opposite side but showing the bag in position;

FIGURE 7 is a fragmentary pictorial view showing the bag-supporting arms as they will appear when moved forwardly to cause closing of a bag;

FIGURE 7a is a fragmentary part-sectional detail view showing the pivoted door locking catch and method whereby it is released when a bag is closed;

FIGURE 8 is a cut-away pictorial view of a bag for a soiled linen cabinet constructed according to the invention;

FIGURE 9 is a pictorial enlarged detail view of the pivoted joint between the two members of the frame arranged to be located against the bottom of the bag as shown in FIGURE 8;

FIGURE 10 is an enlarged fragmentary cross-sectional view showing the bag closing members at the commencement of the closing position with the bag removed;

FIGURE 11 is a similar view showing the bag closing members partly closed;

FIGURE 12 is a similar view showing the bag closing members in their fully closed and locked position; and

FIGURE 13 is a view similar to that of FIGURE 12, but showing the simultaneous unlocking of the door catch when the bag closing members are in their fully closed and locked position.

Referring to the drawings, reference 1 denotes the cabinet of rectangular form mounted on castors 2. A handle 5 is provided for wheeling the cabinet along on the castors 2 as required. Provided on the top end of the cabinet 1, is the rotatably mounted inner drum member 6 located inside of the outer fixed casing 7, having a top opening 8 and a bottom opening 9. The inner drum member 6 has a single opening 10 through which the soiled linen is inserted when this opening coincides with top opening 8 of the outer casing 7 as shown in FIGURE 3. Each of the openings 8, 9, and 10 preferably have an arc length which does not exceed 90°. The inner drum member 6 is provided on its end plates with stub axles 11 which project through apertures in the end plates of the outer casing 7 and are journaled in bearings 12 supported from the top end of the cabinet frame as shown in FIGURES 3 and 5.

The shaking down means at the bottom of the cabinet is made up of two flat plate members 13 and 14 which are hingedly connected along their meeting edges to a transverse pivot shaft 15, the ends of which are slidably located on vertical guiding pins 16 fixed to the cabinet frame. To operate this device, a foot pedal 38 is keyed to a pivot shaft 18 to which two arms 39 are fixed, which arms extend beneath the plate members 13 and 14 and coat with short downwardly directed roller extensions 20 fixed to the pivot shaft 15. Downward pressure on the foot pedal 38 will then raise the pivot shaft 15 so that the plates 13 and 14 assume an inverted V-formation as more clearly indicated in FIGURE 6. On release of the foot pedal 38, the plates 13 and 14 drop back to their inoperative positions and in doing so give the bottom of a bag 21, supported thereon, a positive shock which compacts any soiled linen previously deposited therein.

As shown in FIGURE 8, the bag 21 is square in cross-section and the top edges of two opposite sides of its mouth opening are fixed to closing members 22 and 23 of angle-section which are provided at their ends with supporting projections 24 by means of which the bag is supported in suitable socket fittings provided inside of the cabinet. When the bag is closed, the two bullet nosed pins 25 on the closing member 22 engage in tubular receivers 26 on the closing member 23 and a key operated lock 27 coats with a corresponding catch element in the closing member 23. When the bag 21 is inserted in the cabinet the projections 24 on one closing member are engaged in a pair of front sockets 45 at one side of the cabinet while the projections 24 on the other closing member are engaged in a pair of rear sockets 44 carried by a pair of arms 40.

Access to the interior of the cabinet is provided by a hingedly mounted door 32 on the front side thereof.

Rotary movement of the inner drum member 6 is now effected by means of chain 33 passing around a chain sprocket 34 keyed to a stub shaft 11, and a chain wheel 35 which is arranged to be partially rotated by a foot pedal 36 against the action of a tension spring 37. Operation of the shaking down mechanism is effected by means of the separate foot pedal 38 and arms 39, which coat with the shaft 15. In an alternative arrangement the shaft 15 may be connected by a link 31 to an arm 30 keyed to one of the stub axles 11, so that operation of the inner drum member 6 will simultaneously cause operation of the shaking down mechanism. This modification is shown in chain-dotted outline in FIGURE 2.

Opening and closing of a bag while in the cabinet is effected by the two vertical spaced bag-supporting arms

40 located within the cabinet adjacent to its rear side which arms are pivotally mounted as regards their bottom ends by being keyed to a transverse pivotally mounted shaft 41 arranged to be oscillated by an external hand lever 42.

The top ends of the arms 40 are connected by a cross bracing 43 and each of such ends is provided with a bag-supporting socket 44. In addition, these top ends are bent inwardly at a small angle and are arranged to be a few inches higher than a second pair of bag-supporting sockets 45 pivotally attached to bracket plates 46 projecting inwardly from the door opening. These sockets 44 and 45 are arranged to receive the projections 24 of the two bag closing members 22 and 23.

To insert a bag, the arms 40 are brought to the forward position shown in FIGURE 7 and the projections 24 are inserted in the sockets 44 and 45. The door 32 is now closed and by means of the hand lever 42, the arms 40 are pivoted rearwardly to open the mouth of the bag. When the door 32 is closed, a spring-actuated pivotally mounted latch 47 on the inside of the free edge thereof, engages beneath a stop edge 48 of the door frame so as thereby to lock the door 32 in the closed position. The door can thereafter only be opened when the arms 40 are brought forward so that a striker rod 49 fixed to one of them engages with a short lever extension 50 of the latch 47 so as to cause it to pivot downwardly against the action of its leaf spring 51 so as to release it. In this position, the arms 40 will have caused the lock 27 to have engaged with its counterpart on the closing member 23 of the bag.

To facilitate emptying of a bag, an articulated frame device comprising two shallow U-shaped parts 52 hingedly attached at their ends to a central cross bar 53 having a holed lug or eye 54 fixed to it midway between its ends, is arranged to be located in the bottom of the bag as shown in FIGURE 8. The lug or eye 54 is arranged to pass through a hole in the bag bottom so that a suspension ring 55 engaging therewith is outside of the bag. Stop lugs 56 are provided on the ends of parts 52 arranged to permit free pivoting movement for the shaking down operation but to retain these parts in the same plane when the bag is suspended in the inverted position by the ring 55. The two parts 52 are preferably made from tubular stock.

Reference is now made to FIGURES 5 and 5a showing how decontamination of the inner drum member 6 is effected automatically each time the pedal 36 is depressed. To achieve this result, one end of the inner drum 6 is provided with a bearing 57 which coats with a hollow journal pin 58 suitably held in a holder block 59 supported from a frame member 60 of the cabinet. A pipe or tube 61 is connected by one end to the outer end of the journal pin 58, while its other end is connected to a small pump 62 arranged for intermittent operation by means of a cam 63 keyed to the pivot pin 64 on which the foot pedal 36 is mounted or fixed to the chain wheel 35. The pump 62 is connected to a reservoir 65 containing a suitable liquid disinfectant by a pipe or tube 66.

A simple bacterial filter for the mouth of the bag consisting of a strip 67 of oil-impregnated felt, foam plastic or the like, is arranged to be located above the two tubular receivers 26 of the closing member 23 as shown in FIGURE 8. Handles 68 are attached to the outsides of the closing members 22 and 23 to facilitate handling of a bag.

FIGURES 10, 11, 12 and 13 show more clearly how the bag closing members 22 and 23 are closed together and locked by the key-operated lock 27 which is provided with a locking latch 69 biassed by a spring 70 towards its closed position so that when the two bag closing members 22 and 23 are in their fully closed and locked position as shown in FIGURE 12, the latch 69 will automatically be projected into the locking aperture 71 provided in the bag closing member 23 which

when closed is located on the inside of the bag closing member 22.

Reference 72 indicates the two inwardly folding flat hinge elements connecting the bag closing members 22 and 23, to which elements the top end regions of the two sides of the bag 21 are attached such as by providing a tunnel 73 in such top end regions to receive the hinge elements 72 (see FIGURE 8). The hinge elements 72 are preferably detachably securable to the bag closing members 22 and 23 such as by arranging for the end hinge pins 74 to be removable. The two other opposing sides of the bag 21 are also preferably detachably securable to the downwardly extending flanges of such bag closing members 22 and 23, such as by clamping the top beaded edges thereof to these flanges by clamping plates and the use of bolts or studs, and/or the pins 25 and their tubular receivers or sockets 26, which may have screw-threaded ends for this purpose. In this way the bag 21 is readily removable for replacement purposes such as when damaged or worn out. The strip of impregnated felt 67 constituting the bacterial filter is located between the tubular receivers 26 and the underside of the top flange of the bag closing member 23.

FIGURE 13 shows clearly how, when the two bag closing members 22 and 23 are in their fully closed and locked positions, the end of the striker rod 49 attached to an arm 40, makes contact with the lever extension 50 of the door latch so as to open it against the action of its curved leaf spring 51. Thereafter the door 32 can be opened to remove the locked bag 21, on release of the bolts 75 by the handle 76.

What is claimed is:

1. A cabinet for the collection and storage of soiled linen which includes: a frame enclosed by an outer casing; an inner removable, closable and lockable soiled linen bag-like container within the outer casing including an externally-operable means arranged to open, close and lock a top-openable end thereof; a closable filling opening in the top end of the cabinet through which to deposit soiled linen into the inner container through its said top-openable end but to prevent its removal therethrough; a lockable door opening in a sidewall of said cabinet for placement and removal of said inner container, which door may be unlocked for removal of the inner container only when said inner container has been closed and locked; and, in the absence of access to the inner container for direct manual compression of the soiled linen within the said container, shaking-down means located at the bottom end of the cabinet, supporting the inner container and adapted to compact the deposited soiled linen for increasing the loading of the said inner container, and, as and when it becomes full, for preventing obstruction by the soiled linen of the operation of said closable filling opening, said closing and locking within the cabinet of the inner container and the unlocking of said door; which shaking-down means includes at least one displaceable member located within the outer casing and foot-operated means located externally of the outer casing for actuating the displaceable member.

2. A cabinet for the collection and storage of soiled linen as claimed in claim 1, wherein the closable filling opening includes closure means for operating the same, and wherein said shaking-down means is selectively interconnected with such closure means by a displaceable member located within the outer casing.

3. A cabinet for the collection and storage of soiled linen as claimed in claim 1, wherein the closure means coacting with the top filling opening is so arranged that, although soiled linen can be readily deposited in the cabinet and into the inner container, it cannot be withdrawn through the filling opening.

4. A cabinet for the collection and storage of soiled linen as claimed in claim 3, wherein the closure means is in the form of a horizontally disposed inner drum member mounted within an outer similarly shaped casing for

rotary movement with respect thereto about its horizontal axis, the outer casing having a longitudinal opening along its bottom side and a second longitudinal opening along its top side, the inner drum member being provided with a single longitudinal opening corresponding in size to the openings in said outer casing; such that for filling, the opening in the drum member may be brought into alignment with the top opening in the outer casing and a batch of soiled linen may be deposited in the drum member, which may be thereafter rotated to bring its opening into alignment with the bottom opening in the outer casing so as to allow the contents thereof to be discharged by gravity into said inner container located within the cabinet having a top opening directly beneath the bottom opening of said outer casing; and wherein foot-pedal operated means are provided to cause the required rotary movements of the drum member.

5. A cabinet for the collection and storage of soiled linen as claimed in claim 4 wherein the inner drum member is rotatably mounted by means of stub axles at its ends, said axles being journaled in bearings located at the end walls of the outer casing; at least one of said stub axles projecting through and beyond its bearing; a toothed sprocket wheel keyed to such projecting axle; said foot-pedal operated means for drum movement including a complementary toothed sprocket wheel; and a chain belt operatively interconnecting said sprocket wheels.

6. A cabinet for the collection and storage of soiled linen as claimed in claim 4 wherein the inner drum member is rotatably mounted by means of stub axles at its ends, said axles being journaled in bearings located at the end walls of the outer casing; at least one of said stub axles projecting through and beyond its bearing; an actuating lever arm secured to such projecting axle; and a connecting rod interconnecting said lever arm with said foot-operated shaking-down means.

7. A cabinet for the collection and storage of soiled linen as claimed in claim 6, wherein at least one of said stub axles of the drum member is drilled axially to permit rotation upon a journal pin which constitutes a spray nozzle connected to a pump and to a reservoir of disinfectant fluid; which pump may be activated by cam means provided on the said lower pedal-actuated chain wheel of the chain drive operating the drum member; such that the contents of said drum member is decontaminated as said drum rotates to its soiled linen receiving position.

8. A cabinet for the collection and storage of soiled linen as claimed in claim 6, wherein to provide said shaking-down means the bottom of the cabinet comprises two adjacent flat plate members hingedly connected together by means of a transverse pivot shaft, the ends of which shaft are slidably located by vertical guiding means fixed to the frame of the cabinet; whereby depression of said foot-pedal connected to lever arms extending beneath the bottom of the cabinet causes such pivot shaft to rise and draw said two flat plate members into an inverted V-formation, and raising of said pedal permits said plate members to return to their original positions; whereby the shocks of such return movements are transferred to the bottom of the inner container supported on such articulated plate members, and thereby to the contents thereof, so as to compact such contents.

9. A cabinet for the collection and storage of soiled linen as claimed in claim 8, wherein said connecting rod is pivotally connected to one end of the transverse pivot shaft whereby full depression of said foot pedal rotates said inner drum member about its axis to bring its opening into alignment with said top opening of the outer casing, to enable a batch of soiled linen articles to be deposited therein; and raising of said foot-pedal permits said transverse pivot shaft to fall, thereby causing said inner drum member to rotate through an angular distance sufficient to bring its opening into alignment with the bottom opening of said outer casing and to allow said contents to fall into the inner bag-like container.

10. A cabinet for the collection and storage of soiled linen as claimed in claim 1 wherein the inner removable and closable container is fashioned of flexible sheet material in bag-like form.

11. A cabinet for the collection and storage of soiled linen as claimed in claim 10, wherein the inner removable and closable container is arranged to be locked before it can be removed from the cabinet by way of said lockable door opening in a side wall of the cabinet.

12. A cabinet for the collection and storage of soiled linen as claimed in claim 10, wherein said bag-like container is of square cross section; is suspended by its top mouth end on supporting means within the cabinet; and is arranged to be closed and locked by means of rigid closing members provided along two opposite sides of said top open mouth end; the ends of such closing members being connected by elongated hinge plates which, in the closed position of the container fold inwardly to lie adjacent one another; said closing members being provided with at least one catch mechanism.

13. A cabinet for the collection of soiled linen as claimed in claim 12 wherein opening and closing of said bag-like container within the cabinet is effected by the provision of two vertical spaced bag-supporting arms located within said cabinet adjacent to the rear side thereof, said arms being pivotally mounted at the bottom ends thereof and arranged for actuation by an external hand lever for movement toward and away from the front side of said cabinet; which cabinet is provided with a hingedly mounted door giving access to the interior thereof for the purpose of inserting and removing said bag-like container.

14. A cabinet from the collection of soiled linen as claimed in claim 13 wherein the top ends of said two vertical bag-supporting arms are bent at an angle and are provided each with a fixed carrier socket to receive the ends of a rear bag-closing member; the ends of coacting front bag-closing members being arranged for insertion one in each of two rotatably mounted carrier sockets mounted adjacent to the front side of said cabinet; said front carrier sockets being mounted at a level lower than the carrier sockets on the bag-supporting arms, to facilitate closing of a full bag.

15. A cabinet for the collection of soiled linen as claimed in claim 13 wherein to ensure that said bag-like container is locked before said door may be opened a spring-actuated pivotally mounted latch is provided on the door edge adjacent to a locking handle thereof to engage with a stop located on the cabinet door frame when the door is closed to lock the same; which latch is arranged to be released by a striker rod fixed on one of said two vertical bag-supporting arms which open and

close said bag within the cabinet; such that release of said latch may occur only when such arms have moved the rear bag closing member beyond a locking position with respect to the front bag closing member.

16. A cabinet for the collection of soiled linen as claimed in claim 15 further including a bacterial filter consisting of a strip of impregnated material of the same length and width as the interior of the horizontal face of the front bag-closing member held in position thereagainst.

17. A cabinet for the collection of soiled linen as claimed in claim 12 further including a device to facilitate emptying of a full bag after removal from the cabinet; comprising a two-part frame wherein the said two parts are hingedly attached to a central cross bar, which bar is provided with a holed lug at its mid point adapted to pass through a central aperture located in the bottom of said bag-like container, and to be held therein by means of an external ring; said ring being adapted to engage 20 said hole in said lug, when the device is inverted and lies against the inside surface of the bottom of said bag-like container.

18. A cabinet for the collection of soiled linen as claimed in claim 17, wherein each of the two parts of said 25 two-part frame is of U-form shape, and is bent from tubular material with the ends of the two limbs of each part pivotally connected to the central cross bar by threaded means at the ends thereof; the pivotally mounted ends of the two parts being provided with stop lugs which permit the two parts of said frame to pivot with respect to one another on operation of the shaking-down device, but which hold the two parts in the same plane with one another when the bag is inverted and suspended by the 30 external ring.
